[57] CLAIM

The ornamental design for an expandable shopping bag, as shown and described.

DESCRIPTION

FIG. 1 is a side elevational view of an expandable shopping bag showing my new design in its folded and closed position, the opposite side being a mirror image thereof;

FIG. 2 is an enlarged scale left end view of FIG. 1;
FIG. 3 is an enlarged scale right end elevational view of FIG. 1;

FIG. 4 is an enlarged scale top plan view of FIG. 1;
FIG. 5 is an enlarged scale bottom plan view of FIG. 1;
FIG. 6 is a side elevational view of one side of the bag in its unfolded and expanded position;

FIG. 7 is a top plan view of the bag in its unfolded and expanded position;

FIG. 8 is a side elevational view of the other side of the bag in its unfolded and expanded position;

FIG. 9 is a bottom plan view of the bag in its unfolded and expanded position; and

FIG. 10 is an end view of one end of the bag in its unfolded and expanded position, the other end of the bag being a mirror image thereof in the unfolded and expanded position.
